WEBSTER NOYES BAKER AND RALPH A. MASTEN, OF GLENS FALLS, NEW YORK, ASSIGNEES TO INTERNATIONAL PAPER COMPANY, A CORPORATION OF NEW YORK

METHOD AND MEANS FOR DRESSING GRINDSTONES

Application filed June 19, 1928. Serial No. 286,515.

This invention relates to machines for grinding wood to produce wood pulp for use more particularly in the manufacture of paper, machines for this purpose comprising usually a rotary grindstone against the periphery of which, wood held in a pocket or pockets is forced by suitable feeding means. In connection with these machines, means are provided, usually in the form of a burring tool for dressing or sharpening the grinding surface of the stone when the latter becomes dull or smooth by use, which tool is usually mounted for rotation in a suitable holder and is moved transversely back and forth across the face of the stone while being forcibly pressed against the same, as the latter is rotated and while the wood is being ground, and by such treatment the grinding face of the stone is roughened or sharpened, all as well known in this art.

In the burring action, a considerable amount of gritty, sandy and other material is removed from the stone and is carried around by the same, along with the wood pulp entrained by the stone, and is discharged into the usual pit beneath the stone into which the ground wood or pulp is received. This has been the cause of much annoyance and trouble, for it has been necessary to remove the gritty and sandy material from the pulp by special processes, such for instance, as by the process of sedimentation, for if it is left in the pulp, the subsequent handling of the pulp is interfered with, and defects are of course developed in the paper produced therefrom.

It is the aim of the present invention to prevent this foreign material resulting from the burring action from being discharged in and mixed with the pulp, and the invention consists of the improved method of and apparatus for disposing of this gritty, sandy and other material by removing the same from the stone before it has had a chance to reach the point where the pulp is discharged and collected, and in the specification to follow the invention will be described in detail, and the novel features thereof will be pointed out in the appended claims.

In the accompanying drawings, Fig. 1 is a side elevation of a wood grinder equipped with a stone sharpening mechanism or burring tool and having our invention embodied therein.

Fig. 2 is a plan view on an enlarged scale of the receptacle associated with the burring tool for receiving the sandy or gritty material resulting from the burring operation, the burring tool and its carrying post being shown in dotted lines.

Fig. 3 is a side elevation of the same.

Fig. 4 is a fragmentary view in side elevation, on an enlarged scale, of the grinding stone, the burring tool and associated receptacle, showing in section a fluid jet device for dislodging the gritty material and pulp from the face of the stone and directing the same into the receptacle.

Referring to the drawings,

Referring particularly to Fig. 1, a grindstone 1 is rotatably mounted in a suitable frame 2 equipped with a wood holding pocket 3 in which the wood to be ground is forced against the grinding face of the stone by suitable feeding means well known in the art and not necessary here to illustrate, the ground wood or pulp resulting from the grinding operation being discharged from the stone into a suitable receiving pit 4 beneath the stone.

To sharpen the grinding face of the stone when in continued use it becomes dulled, a burring tool 5 is provided which is rotatably mounted in a support or burr post 6 carried by a slide 7 which latter is moved back and forth so as to cause the tool, while pressed forcibly against the stone to traverse the grinding face of the same during the grinding operation on the wood. In this action of the tool a considerable amount of sandy and gritty material is broken away from the stone and it becomes mixed with the pulp entrained by the stone, and in order to prevent this material from passing into and becoming mixed with the ground pulp in the pit, we provide a receptacle 8 to receive the said material, which receptacle surrounds the lower portion of the burring tool and is firmly fastened to the sides of the forked end of the burring post in which the tool is journaled, as by

means of fastening bolts 9 passing through horizontal slots 10 in the side walls of the receptacle and screwed into the forked end of the post. The form and relation of these parts are such that the edge or lip 11 of the inner wall of the receptacle will be sustained close to the peripheral grinding face of the stone, so that the sandy and gritty material resulting from the burring operation will, along with the pulp entrained by the stone, be delivered into the receptacle and thus prevented from being carried down by the stone and discharged into the receiving pit with the pulp therein.

The material collecting in the receptacle, which will be mixed with water and will form a pool therein, is removed therefrom, in the present instance by subjecting the surface of the collected pool of material to air pressure, as by suction acting beneath said surface, by means of discharge pipe 12 which is extended along the burring post and has its inner open end extended downwardly into the receptacle and terminating near the bottom of the same. By suitable suction means, not shown, applied to the outer end of the pipe, a suction is created therein and the contents of the receptacle thus effectually removed.

In order to prevent the passage into the pipe of coarse particles such as would tend to clog the same, a screen 14 is fixed in the vessel near its bottom and above the open end of the pipe, the screen being of such mesh as to permit the passage through it of particles of such fineness as will readily pass through the pipe without clogging the same.

In the operation of the device, with the grindstone rotating in the direction indicated by the arrow in Fig. 3, and with the wood in the holding pocket pressed against the stone, the burring tool is pressed against the grinding face of the stone and is moved back and forth transversely thereof. In this action with the receptacle 8 moving along with the burring tool, and with its lip in close proximity to the grinding face, the sandy and gritty and other material resulting from the burring operation, together with the wet pulp mixed therewith, will be deflected from the face of the stone and caused to enter the receptacle and will collect in the bottom of the same, and due to the suction through the discharge pipe the material will be continuously removed therefrom. Due to this action there will no liability of the sandy or gritty material finding its way into the mass of pulp discharged from the stone into the receiving pit, and the pulp will therefore be kept free from contamination by such foreign material.

As shown in Fig. 4, a fluid jet 15, in the present case a jet of water, is directed from a jet pipe 16 arranged beneath the lip of the receptacle, tangentially against the face of the stone at a point just above the lip, the effect of which jet will be to dislodge any

material or pulp adhering to the stone, and will deflect the same into the receptacle.

As shown in Figs. 2 and 3, a plate 17 is arranged above the open end of the receptacle at the upper side of the burring tool, and is fixed at its outer end to the burr post and terminates at its inner end closely adjacent the peripheral face of the tool, the purpose of which plate is to prevent the pulp entrained by the moving stone from entering the receptacle, and also prevent the material collecting in the receptacle from being thrown out by the rotation of the burring tool.

By the provision of the horizontal slots 10 in the side walls of the receptacle which receive the fastening bolts, the receptacle may be adjusted horizontally relative to the burring tool to and from the stone, and by this means the proper relation of the lip 11 on the receptacle to the grinding face of the stone may be established.

In the foregoing description and accompanying drawings, we have set forth our invention, both in respect to the apparatus and method involved, in the particular detailed form and construction of the parts and the method of procedure, which we prefer to adopt, and which in practice have been found to answer to a satisfactory degree the ends to be attained. It will be understood, however, that these details may be variously changed by the skilled mechanic without departing from the limits of the invention; and furthermore it will be understood that the invention is not limited, either in respect to the apparatus or method, except insofar as such limitations are specified in the claims.

Having thus described our invention, what we claim is:

1. In combination with a grindstone, a burring tool to dress the grinding face of the stone, a receptacle associated with the burring tool and in position to receive the gritty and other material resulting from the burring operation, a screen in the receptacle, and a discharge pipe entering the receptacle and communicating therewith at a point beneath the screen.

2. In combination with a grindstone, a burring tool to dress the grinding face of the stone, a receptacle associated with the burring tool and in position to receive the gritty and other material resulting from the burring operation, a screen in said receptacle, a discharge pipe entering the receptacle and terminating at its end beneath said screen, and adapted to have suction applied to remove the gritty and other material from the receptacle.

3. In combination with a grindstone, a rotary burring tool to dress the grinding face of the stone, a receptacle associated with said tool in a position to receive the gritty material resulting from the grinding operation, and a plate associated with the receptacle and having its edge disposed adjacent the peripheral

surface of the burring tool at its upwardly moving side to prevent the collected material from being thrown from the receptacle by the tool.

5 4. In combination with a grindstone, a rotary burring tool to dress the grinding face of the stone, a receptacle associated with said tool in a position to receive the gritty material resulting from the grinding operation, and a plate extending over the upper end of 10 the receptacle and having its edge disposed adjacent the peripheral surface of the burring tool at its upwardly moving side to prevent entrance into the receptacle of pulp carried 15 over and onto said tool by the grindstone.

5. In the method of burring grindstones wherein the burring operation is effected by a burring tool held in contact with the moving face of the stone and traversed longitudinally thereof, the step of preventing the gritty and other material removed from the stone in the burring operation from mixing with the pulp, which consists in subjecting the surface of the stone, adjacent the point where the tool acts, and after said tool has acted, to a fluid jet acting on the stone in a direction opposite that of the movement of the stone at that point, to dislodge the material removed by the burring tool, said jet being directed at 20 such angle as to deflect the material dislodged from the stone, collecting the deflected material, and finally discharging the same.

6. In combination with a rotary grindstone, a rotary burring tool engaged therewith and 25 movable longitudinally thereof to traverse the face of the stone, a receptacle associated with the tool to receive the material resulting from the burring operation, a water jet directed against the stone at a point adjacent the point 30 of contact of the tool therewith, and in a direction opposite that of the movement of the stone at that point, to dislodge said material, said jet acting in a direction to cause the dislodged material to be deflected into said 40 receptacle.

In testimony whereof, we have affixed our signatures hereto.

W. NOYES BAKER.
RALPH A. MASTEN.
